Application March 23, 1953, Serial No. 343,930

8 Claims. (Cl. 66—2)

The present invention relates to a device for darning 15 holes in knitted goods.

It is an object of the present invention to provide a machine in which the above operation which so far is carried out by hand can be executed in easy way without any knowledge of the art.

The device according to the invention comprises a means for tensioning the material to be darned, a mechanism for moving a needle up and down which is preferably driven from the bottom side and said needle having an eye for guiding the darning thread, a mechanism for supplying and tensioning uniformly said thread, a means for guiding the needle and supporting the material, pins for picking up and releasing the loops of the thread formed by the needle, a mechanism for moving the pins with regard to each other in a plan that is positioned 30 perpendicularly to the direction of movement of the needle and a mechanism for reciprocating the pins in an axial direction.

In the drawings an embodiment of the device according to the invention is shown by way of example.

Figure 1 shows a side elevation with a partial section. Figure 2 shows a plan view with a partial section.

Figure 3 shows a front elevation with a partial section.

The Figures 4 and 5 show how a loop formed by the needle is picked up by a pin.

The figures show the machine frame 1 in which a wheel 2 is driven by means of a pulley 3. This wheel 2 is fixed onto a shaft 4 rotatable in bearings 5 and 6. On the shaft 4 a gear 7 is attached by means of a key. A second shaft 8 is rotatable in bearings 9, 10 and 11. A gear 12 can be shifted on said shaft 8. In a position which is given in the figure said gear 12 is loosely rotatable about the shaft 8 and meshes with the gear 7. In another position which is not shown said gear 12 is connected to the shaft 8 by means of a key 13. The shifting movement in the position abovementioned is carried out by means of a lever 14 rotatable about an axle 15. Said lever is connected in a movable way to a hub 16 of said gear 12 and projects through an aperture 18 in the frame 1 in the shape of a handle 17. The bevel wheel 19 is integral with gear 12. Said bevel wheel 19 is adapted to cooperate with a bevel wheel 20 which is fixed on the shaft 8, through a transmission gear 21.

In the one position of the gear 12 the shaft 8 will rotate in one direction and in the other position it will rotate in an opposite direction. The shaft 8 has at its opposite end a sleeve 22 containing a groove 23 which in a known way can move a thread guide 24 up and down. The rotation of the shaft 8 also operates the up and down movement of a needle 25. On the shaft 8 there is a gear 26 which rotates the shafts 30 and 31 through three other gears 27, 28, 29. The purpose of said rotating shafts 30 and 31 will be explained afterwards. Further a bevel gear 32 is attached on the shaft 8. Said gear 32 rotates an upright shaft 34 through another bevel gear 33. The function of said shaft 34 will be explained afterwards.

The article to be darned, e. g. a sock or stocking, is shifted over a tensioning means 35 in such a way that the hole is at the top side thereof and in such a way that the needle 25 can move up and down through the edge of said hole. The tensioning means 35 comprises a frame which at least is open at the top side and at the side in which the arm 36 with the driving arm of the thread guide 24 and the needle 25 can be inserted. The article to be darned is fastened with the aid of clamping means 37 in a circumferential edge or rim 39 of the tensioning means 35. The clamping means 37 are pulled inwardly by springs 39 in apertures of the base 41 of the tensioning means by which their U-shaped ends 42 can press in the circumferential rim 38 against the article to be darned. Therefore, said article is tensioned on the tensioning means 35. Said tensioning means 35 comprises a base 41 that is carried out as a sledge, the edges 43 of which can move transversely in grooves 44. Said grooves 44 are made in a second sledge 45 which is adapted to make a lengthwise movement with its edges 46 on rails 47. Therefore, the tensioning means 35 with the article tensioned thereon is adjustable in two directions with regard to the needle 25 which can move up and down so that all edges along the hole of said article can be reached and worked upon. The distance of the bottom sledge 45 can be adjusted by hand. This is carried out by means of a handle 48 which projects from the frame 1. Said handle works on a pawl wheel 50 by means of a pawl 49. It works in such a way that by one single movement of the pawl the pawl wheel can be shifted over 1, 2, 3 or 4 teeth, by which the sledge can be adjusted over a predetermined distance with one movement. The pawl wheel 50 is attached to a shaft 51 rotatable in bearings 52 and 53 in the frame 1. A gear 54 is attached to the shaft 51. Said gear meshes in a rack 55. Said rack forms a part of the opposite side of the sledge.

Further the sledge 45 is provided with a fixing means comprising a resilient finger 56 which projects in a row of teeth 57 integral with the frame 1. The possibility of an undesirable movement of the sledge 45 is therefore excluded.

The movement of the topmost sledge 41 is an automatic one in both directions. Said sledge 41 is moved by the upright shaft 34. Said shaft is provided at its bottom end with an eccentric 58 which is rotatable in a frame on the one end of a two-armed lever 60. The rotation of the eccentric 58 gives two movements to the other end of the lever 60, i. e. an oscillating movement in transverse direction and an up and down movement in longitudinal direction. For this purpose the lever 60 is somewhat movable lengthwise in its pivot 61. The end 62 of the lever 60 is Y-shaped and rests on an inclined surface 63. At the end 62 of the lever 60 there is at the top side a finger-shaped projection 64 which is adapted to mesh in a row of teeth 65 at the bottom side of the sledge 41. The projection 64 is provided with some teeth which correspond with the row of teeth 65. By the twofold movement of the end 62 of the lever 60 the projection 64 is adapted to describe a path which has the shape of a flattened O and thereby the sledge 41 will be moved stepwise; its edges 43 sliding in the grooves 44 of the sledge 45. As the teeth 65 are rather long (vide Figure 1) the projection 64 will do its work in all positions of the sledge 45 relatively to the sledge 41.

The transverse stroke of the lever 60 is adjustable. The adjustment can be carried out by shifting the pivot 61 lengthwise along said lever by which the lever arm 66 varies its length. By reversing the rotation of the shaft 34 the finger-shaped projection 64 will also make the O-shaped path in a different direction. Therefore

the stepwise movement of the sledge 41 will take place in a reversed direction.

Pins 69 and 70 are attached to the shafts 67 and 68 and are adapted to rotate therewith. Their means of attachment comprises sleeves 73 and 74 shiftable on the shafts 67 and 68 along keyways 71 and 72. The pins 69 and 70 are removable from said sleeves. Said sleeves 73 and 74 are provided at their ends with flanges 75 and 76. The shafts 67 and 68 are driven by gears 77 and 78 through gears 79 and 80. The gears 79 and 80 are attached on shafts 81 and 82 which receive their rotational movement through bevel wheels 83, 84, 85 and 86. The bevel wheels 85 and 86 are mounted on the extensions 87 and 88 of the shafts 30 and 31. The shafts 87 and 88 can be shifted in the bores 89 and 90 of the shafts 30 and 31 along key-ways 91 and 92. Springs 93 and 94 are inserted in the hollow shafts 30 and 31 which press the extensions 87 and 88 out of the bores 89 and 90 of the shafts 30 and 31. The assembly of the gears 77, 78, 79 and 80, the shafts 81 and 82, the gears 83-86, the shafts 87 and 88 is shiftable lengthwise of the machine in such a way that either the one half is in front of the other half or vice versa. The two halves therefore are mounted in shiftable frames 95 and 96 which are provided with parallel tooth racks 97 and 98 between which a pinion 99 can rotate. The top tooth rack 97 is provided with a handle 100 which projects through an aperture in the frame 1. If said handle 100 is moved e. g. in the direction of the arrow B then the assembly comprising the shaft 87, the bevel wheels 83 and 85, the shaft 81, the gears 77, 79 and the shaft 73 with the pin 69 moves in the direction of the arrow B, the other gears, shafts and pin 70 moving in the opposite direction indicated with the arrow A. The pins 69 and 70 are always in the same horizontal plane, however, also always in different vertical planes.

Additionally each of the pins 69 and 70 is adapted to make an oscillating movement in its own longitudinal direction, however, only if they are positioned inwardly with regard to the needle 25. Such a position is shown in Figure 2 for the pin 70.

The reciprocating mechanism is carried out as follows: Helical springs 101 and 102 are mounted between the inner walls of the frames 95 and 96 and the flanges 75 and 76. Said springs therefore can pull the sleeves 73 and 74 and therefore also the pins 69 and 70 inwardly. On the sleeves 73 and 74 there are flanges 103 and 104 at the outside of the frame 99 and 96. Said flanges being provided with cams 105 and 106. Said cams 105 and 106 are adapted to cooperate during the rotation of the sleeves 73 and 74 with the cams 107 and 108 on the outside walls of the frames 95 and 96. On rotating the shafts 67 and 68 the cams 105 and 107 or the cams 106 and 108 shift over each other. They are pressed against each other by the springs 101 and 102. However, the sleeves 73 and 74 with their pins 69 and 70 can never carry out an oscillating movement at the same time since there are hook-shaped members 109 and 110 on the frame 1 at both sides, said hook-shaped members gripping behind flanges 111 and 112 on the sleeves 73 and 74 if the frames 95 and 96 are moved in the direction of the arrow A. Therefore the pin lying at the outside (vide the pin 69 in Figure 2) will be arrested in its own longitudinal retracted position.

The free ends of the pins 69 and 70 have a larger diameter 113 and 114 in which oppositely directed screw-line-shaped grooves 115 and 116 are provided, said grooves forming an angle with each other which lies at the top side. The device described above operates as follows:

The article to be darned is shifted over the tensioning means 35 and is fixed in the circumferential edge 38 thereof by the clamping means 37. The needle 25 provided with a thread goes up and down on rotation of

the wheel 2 and forms loops 117 (vide Figure 4 and following) by retracting through the support 118. Each loop is picked up by the pin 70 which oscillates at that moment. The needle being in its lowest position the sledge 41 automatically makes a short transverse movement by which the article on its support is shifted and by which the next loop is made by the needle through the article on the right place. The loops are shifted further on the pin by its rotation. In the meantime the needle 25 has made a new loop which is treated in the same way. When the edge of the article to be darned is completely provided with loops then the machine is stopped at the end of said first course of loops and the pins 69 and 70 are displaced with regard to each other by shifting the handle 100. The topmost sledge 45 is shifted in a forward direction depending on the size of the loop over one or more teeth by a movement of the lever 48. Then the rotation of the shaft 34 is reversed and also the rotation of the pins 69 and 70. This is carried out by setting the lever 17. When the wheel 2 rotates again the needle 25 moves through the freshly formed loops. If a loop is formed said loop is picked up by the other pin 69. As the pins rotate continuously in opposite direction and as their ends are provided with oppositely directed grooves 115, 116 they easily pick up and release said loops. The article to be darned is moved with regard to the needle 25 at the right moment by the sledge 41. Therefore the loops are placed on the pins 69 and 70 one next to each other. The loops formed by the needle 25 are initially placed on the first pin and are fixed by the next course of loops after which they are shifted from the pin one by one. In the meantime new loops being shifted on the other pin.

At the end of the darning operation a U-shaped crochet hook is brought over the empty pin, said crochet hook being fixed into the sleeve by means of a bayonet catch, said crochet hook picking up the loops for the last course. The last loop then is pulled through the last course. Therefore all loops are fixed if the end of the thread is pulled.

The machine is equipped with four sets of pins having a diameter of e. g. 1, 2, 3 or 4 mm. The straight portion thereof is somewhat thinner than the rest. Also four different kinds of needles are necessary, having different eyes.

The eye of the needle must be as close as possible to the point.

What we claim is:

1. A device for darning holes in knitted goods comprising a means for tensioning the article to be darned, a mechanism for moving a needle which is preferably driven from the bottom side, said needle having an eye for guiding the darning thread, a mechanism for supplying and tensioning uniformly said thread, a means for guiding the needle and supporting the material to be darned, pins for picking up and releasing the loops of the thread formed by the needle, a mechanism for moving the pins with regard to each other in a plane that is positioned perpendicularly to the direction of movement of the needle and a mechanism for reciprocating the pins in an axial direction.

2. A device according to claim 1, characterized in that the tensioning means comprises a housing with an aperture at its side through which the needle will work upon the article to be darned, said tensioning means being provided with edges along the aperture in which clamping means can press said article under the pressure of springs.

3. A device according to claim 2, characterized in that the tensioning means is movable in a plane perpendicular to the direction of movement of the needle.

4. A device according to claim 3, characterized in that the mechanism for moving the tensioning means comprises two sledges which are shiftable with regard to each other, a driving means of the one sledge being

coupled to the mechanism for moving the needle in such a way that after each stroke of the needle the sledge is moved over a predetermined distance and in a predetermined direction, the driving means of the other sledge being adapted to be displaced stepwise over a predetermined distance.

5. A device according to claim 1, characterized in that the mechanism for displacing the pins in an axial direction is coupled in such a way to the mechanism for moving the needle that the pin which picks up the loops formed by the needle carries out the axial movement, the pin supporting the already formed loops and releasing same carrying out no movement in an axial direction.

6. A device according to claim 5, characterized in that said pins rotate about their axes in opposite directions.

7. A device according to claim 6, characterized in that the pins are provided at their free ends with a larger diameter with such a helical groove that the loops are moved thereon and thereoff respectively by the rotation of said pins, the groove on the one pin being oppositely directed to the groove on the other pin.

8. A device for darning holes in knitted goods comprising a means for tensioning the article to be darned, a mechanism for moving a needle which is preferably driven from the bottom side, said needle having an eye for guiding the darning thread, a mechanism for supplying and tensioning uniformly said thread, a means for guiding the needle and supporting the material to be darned, pins for picking up and releasing the loops of the thread formed by the needle, a mechanism for moving the pins with regard to each other in a plane that is

positioned perpendicularly to the direction of movement of the needle and a mechanism for reciprocating the pins in an axial direction, said tensioning means comprising a housing with an aperture at its side through which the needle will work upon the article to be darned, said tensioning means being provided with edges along the aperture of which clamping means can press said article under the pressure of springs, said tensioning means being movable in a plane perpendicular to the direction of movement of the needle, said mechanism for moving the tensioning means comprising two sledges which are shiftable with regard to each other, a driving means of the one sledge being coupled to the mechanism for moving the needle in such a way that after each stroke of the needle the sledge is moved over a predetermined distance and in a predetermined direction, the driving means of the other sledge being adapted to be displaced stepwise over a predetermined distance and comprising a mechanism by means of which the direction of movement of the one sledge, the rotation of the pins and the movement of the needle are coupled, said mechanism being adjustable in such a way that the direction of movement of the one sledge and the rotation of the pins can be reversed.
